United States Patent Office.

BENEVILLE L. FETHEROLF, OF TAMAQUA, PENNSYLVANIA.

Letters Patent No. 104,565, dated June 21, 1870.

IMPROVEMENT IN TATTING-SHUTTLES.

The Schedule referred to in these Letters Patent and making part of the same.

To all whom it may concern:

Be it known that I, BENEVILLE L. FETHEROLF, of Tamaqua, Schuylkill county, State of Pennsylvania, have invented certain new and useful Improvements in Tatting-Shuttles, and do hereby declare that the following is a full, clear, and exact description thereof, reference being had to the accompanying drawing making a part of this specification, in which—

Figure 1 is a view of the shuttle in readiness for working.

Figure 2 represents a sectional view.

Figure 3, a view of the bobbin.

The nature of my invention consists in the construction of a tatting-shuttle, as more fully hereinafter set forth.

In the annexed drawing—

A represents the body of the shuttle, which is made of metal, and tapers from one end to a point, where the tatting-hook D is formed. This body is hollowed out in the usual manner to receive the bobbin, and has the usual slot B on its side for the passage of the thread from the bobbin.

Upon the inner sides of the end opposite the point is a female screw, whereby the solid heel E is secured by its male screw.

Within the heel is formed an aperture to correspond with the aperture made at the point, so as to form journal bearings for the journals on the bobbin.

In the aperture in the heel is placed a small rubber cushion, x, and upon this cushion bears the bushing E. This bushing is of harder metal than the heel C, and is placed for the purpose of holding the rubber and making the tension in the aperture, and it gives

a more durable bearing for the journal on the bobbin. Without this bushing, when the shuttle is in use, it would soon wear and enlarge the aperture, so that the reel or spool would come in contact with the inner wall of the cylinder, thereby impeding its revolutions.

The body A and the tapering point are made of one piece. The crochet-hook forming the extreme point is made of steel, and tinned before placing it into the mold, and the metal being poured hotter than the tin on the steel hook, solders it into a complete body.

It will be seen that the head or heel C is solid and nearly square on its outer end. Were this otherwise, (tapering, for instance,) it would always be in the way of the hand, or two last fingers of the hand, in working, and of no use. The loop will also pass off the shuttle quicker and easier than it would if the head were formed otherwise.

Having thus fully described my invention,

What I claim, and desire to secure by Letters Patent, is—

1. The head C, provided with the hard-metal bushing E, and rubber x, in the aperture on its inner end, substantially as and for the purposes set forth.

2. The within-described tatting-shuttle, composed of the body A, with point D, head C, with bushing E, and rubber x, screwed to the body for securing the bobbin, all substantially as set forth.

B. L. FETHEROLF.
